ATTORNEY;

UNITED STATES PATENT OFFICE.

WILLIAM W. SLOANE, OF CHICAGO, ILLINOIS, ASSIGNOR TO GOODMAN MANUFACTURING COMPANY, OF CHICAGO, ILLINOIS, A CORPORATION OF ILLINOIS.

CONTROLLER.

Application filed September 26, 1921. Serial No. 503,318.

To all whom it may concern:

Be it known that I, WILLIAM W. SLOANE, a citizen of the United States, residing at Chicago, in the county of Cook and State of Illinois, have invented an Improvement in Controllers, of which the following is a specification.

This invention relates to improvements in controllers for electric railway systems, and has for its object to produce means for quickly breaking the engagement of the controller contacts so as to minimize arcing of the electric current.

Broadly speaking, the invention consists in interposing an operating mechanism between the controller handle and the controller drum by which the drum may be advanced through successive positions in the usual manner, but when turning off the current, the mechanism automatically retains the controller drum in one contacting position until the handle has been moved substantially to the next succeeding position. During this movement of the handle, it actuates a tension device which stores up energy, and when the handle reaches a predetermined point, a latch device releases the tension device which quickly moves the controller drum into the next contacting position, whereby arcing between successive drum contacts is minimized.

The invention may best be understood by reference to the accompanying drawings in which Figure 1 is a top plan view of a controller of a standard construction to which my invention has been applied.

Fig. 2 is a fragmentary view showing the upper end of the controller with the casing removed.

Fig. 3 is an enlarged detail view of the quick break mechanism and casing, with the controller handle removed.

Fig. 4 is a detail view in perspective of one part of the quick break mechanism.

Figs. 5 and 6 are views in perspective of other parts of the quick break mechanism.

Fig. 7 is a diagrammatic view showing the mechanism in the "off" position.

Fig. 8 is a diagrammatic view showing the mechanism in the "on" position.

Fig. 9 is a diagrammatic view similar to Fig. 8 but showing the controller handle rotated into position to release the quick

break mechanism so as to move the controller drum into its next succeeding position. 55

In the embodiment of my invention illustrated in the drawings, my device is shown as applied to a controller 1 of a standard pattern provided with a reversing drum 2 and a contact drum 3. A series of contact 60 fingers 4, 4, are adapted to engage successive contacts 5, 5, carried by the controller drum 3 in the usual manner. An interlocking device of the usual construction is also provided which prevents operation of the reversing drum, excepting when the controller drum 3 is in "off" position as shown in Fig. 1. In the drawings, this interlocking device comprises a rocking arm 6 having engagement with a star wheel 7 on the reversing drum 2 and controlled by a second rocking arm 8 having engagement with a star wheel 9 carried by the controller drum 3. It is to be understood, however, that the parts described are not essential parts of 75 my invention, but are shown for the purpose of illustration.

As heretofore constructed the handle 10 for actuating the controller drum 3 is usually connected directly with the shaft 11 of 80 this drum. In the present invention, this handle is connected to a cam member 12 shown in Fig. 4 which is rotatably mounted on a sleeve 13 which, in turn, is mounted on a hub member 14 engaging the upper end 85 of the controller drum shaft 11. A casing 15 is provided for the quick break mechanism and is enclosed by a cover plate 16 having the cam member 12 attached to its lower face and the handle 10 attached to its upper face as shown in Fig. 4. A frame 17 has a hub portion comprising two spaced ring portions 18, 18, inserted between vertically spaced hub portions 19, 19, of the cam member 12. The hub portions 18, 18, of the frame 17 are splined or otherwise connected to the sleeve 13 and through the hub member 14 is arranged so as to move with the controller drum 3. In other words, the arrangement is such that the cam member 12 is connected to and moves with the handle 10, while the frame 17 is connected to and moves with the controller drum 3. A tension member is interposed between the cam member 12 and sleeve 13, which comprises 100 a spiral spring 20 connected at the outer end 105

to a pin 21 carried by the cam 12 and at the inner end to the sleeve 13 by any suitable means such as a screw 22. Tension is normally provided in the spring 20 so as to maintain a pair of stops 23, 23, on the frame 17 engaged with a pair of shoulders 24, 24, carried by the cam member 12 as shown in Fig. 3, but allows the handle 10 and cam member 12 carried therewith to be rotated against tension a limited distance with respect to the frame 17, sleeve 13, hub 14 and controller drum shaft 11.

A latch device 25 is mounted adjacent the periphery of the arm member 17, which is shown in detail in Fig. 6, and comprises a dog 27 having a pair of pivot pins 28, 28, which are inserted in suitable slots 29, 29, formed in the faces of the frame 17 as shown. The dog 27 is also connected with a tension device, comprising a link 31 pivotally connected to the dog 27 at a point 32 intermediate the pivot pins 28, 28, in the outer end 30 of said dog. The link 31 is also pivoted with a pair of pivot pins 33, 33, which are inserted in suitable slots 34, 34, in the frame 17, opposite the slots 29, 29, already described as containing the pivot pins 28, 28, of the dog 27. The outer end 35 of the link 31 is arranged to extend laterally beyond the boundary of the frame 17 and is provided with a spring 36 retained by suitable means such as a collar 37 and pin 37^a. Said spring engages a pair of shoulders 38, 38, on the frame 17, and is arranged so as to maintain the outer end of the dog 27 in engaging position with the several recesses formed in the casing 15, and also provides a cushioning effect to the frame when the dog 27 is brought to a sudden stop in these recesses, as will hereinafter more fully appear in the description of the operation of the device. The inner end 39 of the door 27 is provided with a cam surface 40 adapted to engage a cam surface 41 on the cam member 12. A cushioning device is also provided on the cam member 12, to become operative as the dog 40 engages the cam surface 41. This cushioning device comprises an impact piece 42 extending above and below the cam surface 41 and movably mounted on a pin 43 carried in a recess 44 formed in the periphery of the cam member 12. A spring 45 is interposed between the impact piece 42 and a shoulder 46 at one end of the recess 44, and normally maintains the impact piece 42 in engagement with a shoulder 47 at the opposite end of the recess. A pair of laterally extending arms 48, 48, are carried by the frame 17 which straddle the cam surface 41 and engage opposite ends of the impact piece 42 at the same time that the dog 27 is moved into engagement with the cam surface 41.

Suitable recesses are formed in the casing 15 so as to be engaged by the outer end 30

of the dog 27 at predetermined points corresponding with the various operating positions of the controller drum. In Figs. 3 and 7 the dog 27 is in the recess 50, and the controller drum is in "off" position. The controller drum shown has six running positions, represented by recesses 51, 52, 53, 54, 55 and 56. These recesses correspond respectively with the notches 50^a, 51^a, 52^a, 53^a, 54^a, 55^a and 56^a on the star wheel 9 of the interlocking mechanism.

It will be observed that the device illustrated herewith comprises a self-contained unit which may be applied to a controller of standard design by removing the ordinary handle from the drum shaft 11, and fitting the sleeve 14 over the end of said shaft. The casing 15 may be secured to the top of the controller by suitable means, such as bolts 15^a, 15^b. This construction is preferable, of course, in applying my invention to controllers of the type shown, but it is manifest that modifications may be made in controller design so as to enclose the operating mechanism within the controller casing if desired.

The operation of the mechanism is as follows:

In Figs. 1 and 3 and in the diagram in Fig. 7, the controller drum is in "off" position with the dog 27 engaged in recess 50. As already described, the tension on the spiral spring 20 maintains the stops 23, 23, on the frame 17 in engagement with the cam member 12 as shown in these figures. When it is desired to rotate the drum into the first operating position, handle 10 is rotated in a clockwise direction. It will be observed, that there is no relative movement of the cam member 12 and the frame 17 while moving the handle in this direction, so that the entire mechanism is turned until the dog 27 engages in recess 51, in the first running position. Similarly the drum may be advanced through its successive positions indicated by recesses 51, 52, 53, 54, 55, and 56. In other words, the controller drum may be advanced to any desired point in the usual manner, and, while so doing, the quick break mechanism remains inoperative. When it is desired to reduce the current, however, as for instance from "on" position shown in Fig. 8 to the next succeeding position, the handle is rotated in a counter-clockwise direction and the frame 12 is carried with it, producing an increased tension on the spiral spring 20, which is transmitted to the frame 17 and tends to move the frame and drum in a counter-clockwise direction. The frame 17, however, is restrained from movement by the dog 27 which is engaged in notch 56 as shown in Fig. 9. In order to release the dog 27, the handle 10 is turned until the cam surface 41 is brought into engagement with the rear end 39 of said dog.

The dog 27 is then rocked on its pivot until its outer end is withdrawn from the notch 56. Owing to the considerable tension of the frame 17 through the spring 20, said frame will be quickly rotated so as to disengage the dog 27 from the cam 41. The dog, being under tension of the spring 36 is immediately thrown outwardly so as to be engaged in the next successive recess 55 adjacent the recess 56.

It will also be observed that, as the cam 41 first engages the inner end 39 of the dog 27, laterally extending arms 48, 48, carried by the frame 17 are simultaneously engaged with the impact piece 42 of the cushioning device carried on the cam member 12, and compress the spring 45. The releasing action of the dog is thus retarded slightly, which requires a small additional effort of the operator which is desirable to indicate when this point is reached. Furthermore, the spring 45 is compressed so as to impart an additional impulse to the frame 17 after it is released and moves into its new position.

The force of impact of the dog 27 as it is stopped in each successive recess is cushioned by the spring 36 on the link 31. Pivot pins 28, 28, of dog 27, and pivot pins 33, 33, of link 31 are movably mounted in slots 29 and 34 respectively, so as to afford the necessary movement of the spring and dog in cushioning this shock.

Altho I have shown and described one form in which my invention may be embodied, it will be understood that many other means may be employed for accomplishing the same results without departing from the spirit and scope of my invention. I do not therefore wish to be understood as limiting myself to the specific construction illustrated herein excepting as specifically limited in the appended claims.

I claim as my invention:

1. In a controller provided with a contactor drum and an operating member, means including a tension member interposed between said drum and said operating member and affording limited relative movement therebetween, latch mechanism associated with the drum and adapted to successively engage a series of stops corresponding to several contacting positions of said drum, means actuated by said operating member for releasing said latch mechanism, and means associated with said latch mechanism for cushioning the impact thereof as the successive stops are engaged.

2. In a controller provided with a contactor drum and an operating member, means including a tension member interposed between said drum and said operating member and affording limited relative movement between said drum and operating member, latch mechanism associated with

the drum and adapted to successively engage a series of stops corresponding to several contacting positions of said drum, means actuated by said operating member for releasing said latch mechanism, and auxiliary tension means carried by one of said relatively movable members and co-acting with said releasing mechanism to impart additional momentum to the drum at the moment of releasing the latter.

3. In a device of the class described, a frame and a cam member both rotatably mounted, spring means connecting said frame and cam member, a rocking dog mounted on said frame adapted to successively engage a series of stops, tension means for said dog, means positively limiting the relative movement of said frame and cam member when rotated relatively in one direction, and means on said cam member for disengaging said dog when the frame and cam member are rotated relatively in the opposite direction.

4. In a device of the class described, a rotatably mounted frame, tension means adapted to rotate said frame, a series of stops, and latch mechanism carried by said frame adapted to successively engage said stops, comprising a rocking dog mounted in said frame, means affording limited lateral displacement of said dog in the direction of rotation of said frame, tension means restraining the lateral displacement of said dog, and means for rocking said dog out of engagement with said stops.

5. In a device of the class described, a rotatable frame, tension means adapted to rotate said frame, a series of stops, and latch mechanism carried by said frame adapted to successively engage said stops comprising a rocking dog, means affording limited lateral displacement of said dog in the direction of rotation of said frame, a rocking link having pivotal connection with said dog, means affording limited lateral displacement of said link, tension means co-operating with said link in a direction tending to throw one end of the dog outwardly into engagement with the stops, and means for rocking said dog out of engagement with said stops.

6. In a device of the class described, a rotatable frame, tension means adapted to rotate said frame, a series of stops, and latch mechanism carried by said frame adapted to successively engage said stops, comprising a rocking dog, means affording limited lateral displacement of said dog in the direction of rotation of said frame, a rocking link having pivotal connection with said dog, means affording limited lateral displacement of said link, tension means co-operating with said link in a direction tending to throw one end of the dog outwardly into engagement with the stops and to restrain the lateral displacement of said dog, and

means for rocking said dog out of engagement with said stops.

7. In a device of the class described, a frame and a cam member, both rotatably mounted and having limited relative movement therebetween, spring means connecting said frame and cam member, a rocking dog mounted on said frame adapted to successively engage a series of stops, tension means for said dog, means positively limiting the relative movement of said frame and cam member when rotated relatively in one direction, means on said cam member for disengaging said dog when the frame and cam member are rotated relatively in the opposite direction, and auxiliary tension means mounted on one of said relatively movable members adapted to be placed under compression by the other member during a portion of the relative movement of the said members, and prior to the disengagement of said dog.

8. In a device of the class described, a frame and a cam member both rotatably mounted, spring means connecting said

frame and cam member, a rocking dog mounted on said frame adapted to successively engage a series of stops, tension means for said dog, means positively limiting the relative movement of said frame and cam member when rotated relatively in one direction, means on said cam member for disengaging said dog when the frame and cam member are rotated relatively in the opposite direction, and auxiliary tension means mounted on one of said relatively movable members adapted to be placed under compression by the other member during a portion of the relative movement of the said members, and prior to the disengagement of said dog. 30

Signed at Chicago, in the county of Cook and State of Illinois, this 23rd day of September, 1921.

WILLIAM W. SLOANE.
